HIGH SPEED TAPE READER MECHANISM

Robert M. Brink, New Canaan, Conn., assignor to Time, Incorporated, New York, N.Y., a corporation of New York

Application May 22, 1953, Serial No. 356,771

9 Claims. (Cl. 271—2.4)

This invention relates generally to the art of motion control mechanisms adapted to produce intermittent states of dwell and high speed motion for an elongated strip of material, and more particularly to the art of motion control mechanisms adapted to produce the aforesaid alternate states for a tape which bears indicia, to control the operations of a utilization device, such as a printing apparatus.

In motion control mechanisms of the type described, it is apparent that since there is always some mass involved which must be accelerated or decelerated, a certain period of time (which may be called a time lag) is always required for the transition of the condition of the strip from a state of rest to a state of motion or the reverse. This time lag, which represents a non-utilizable period in an alternation cycle between two states, is proportional only to the ratio of accelerated or decelerated mass to the applied force, the time lag being independent of the frequency of alternation. As the frequency of alternation increases, therefore, the time lag interval occupies an increasing portion of each alternation cycle at the expense of the utilizable portion of the same. The time lag between the states of dwell and motion of a strip thus determines the highest frequency of alternation at which a motion control mechanism can be employed.

In the prior art, motion control mechanisms are known which may be adapted to produce alternate dwell and high speed motion states for a strip of elongated material. In these devices, however, the control over the motion of the strip is exerted by a positive drive, such as for example a sprocket wheel which engages holes in the strip, or a driven roll which frictionally contacts the strip in a non-slipping manner. Accordingly, in the prior art devices the mass involved which must be accelerated and decelerated is the relatively large mass of the member which contacts the strip, together with the mass of the arrangement which drives the member. As a result, such positive drive systems are characterized by long time lags limiting them to low frequencies of alternation. A limitation of this sort may be extremely disadvantageous where the strip and motion control mechanism are associated with a utilization device which can otherwise respond at a much more rapid rate.

It is an object of the invention, accordingly, to remedy the above noted deficiencies in the prior art.

Another object of the invention is to provide new and improved mechanism for producing rapidly alternating motion and dwell states for a strip of elongated material in which the only mass which determines the time lag of the strip between states is that of the strip itself.

A further object of the invention is to provide for firm grasping of the strip when arrested from motion.

A still further object of the invention is to provide a yieldable strip driving force to guard against tearing of the strip when rapidly decelerated.

According to the invention, an elongated strip of material, as for example an indicia bearing, magnetic tape is urged to motion by a driving mechanism which exerts a

continuous but yieldable driving force on a portion of the strip. Ahead of the driving mechanism is located a pair of jaw members which may be selectively closed or opened to grasp or release, respectively, another portion of the strip. When the jaws are closed, the grasping action of the same is sufficient to overcome the driving force on the strip imparted thereto by the driving means with the result that the strip remains stationary in a state of dwell. Intermittently, however, the jaws are opened by an actuator, for example a solenoid, with the result that the strip first rapidly accelerates to a state of high speed motion, and then, upon subsequent deenergization of the actuator, the strip is rapidly decelerated to return to the dwell state. In the course of the transition from one state to another, the only mass which determines the time lag of the strip is that of the strip itself, with the result that the time lag is minimized and the frequency of alternation between states which may be employed is maximized.

For a better understanding of the invention, reference is made to the accompanying detailed description of a representative embodiment as shown in the figures of the accompanying drawing in which:

Figure 1 is a diagram in perspective of the motion control mechanism and the elongated strip of material moved thereby;

Figure 2 is a schematic diagram of an apparatus with which the motion control mechanism is associated;

Figure 3 is a fragmentary view of a narrow magnetic tape with indicia groups therein extending along the tape length;

Figure 4 is a sectional view of another form of mechanism for imparting driving force to the tape; and

Figure 5 represents in sectional view yet another form of force imparting mechanism.

Referring now to Figure 1, a strip of elongated material, in the present instance, shown as a length of magnetic tape and designated by the number 10 passes between two oppositely disposed longitudinally extending sections 12 and 13 of a pair of continuous fabric belts 14 and 15, respectively. The length and position of section 12 is formed by passing belt 14 over and around a driving roll 16 and an idler roll 17, both of which rolls are supported as described below by a base 18 which also acts as the support for the other major elements of the tape control mechanism.

The driving roll 16 is rigidly mounted on a transverse shaft 19 having opposite ends thereof journaled in a pair of supporting standards 20 (only one of which is shown) upon the base 18. Similarly the idler roll 17 is mounted on a transverse shaft 23 having opposite ends journaled in standards 24 and 25. The position of the standards 24 and 25 upon the base 18 may be adjusted by set screws 26.

The shaft 19 is provided with a pulley 30 which is driven by a belt 31 driven in turn by a driving pulley 32 carried by a drive shaft 33 journaled in standards 34 and 35 on the base 18. The shaft 33 is driven through conventional coupling 36 by a constant speed motor 37, as for example a synchronous motor.

In a similar manner, the longitudinally extending section 13 of belt 15 is formed by the passing of the fabric belt 15 over and around a driving roll 38 and an idler roll 39 both of which rolls are supported, as described below, from an upper plate 40.

The driving roll 38 is rigidly mounted on a shaft 41 having opposite ends journaled in a pair of standards 42 beneath the upper plate 40 at opposite transverse edges thereof. The idler roll 39 is mounted on a similar transverse shaft 44 having opposite ends journaled in standards 45 and 46 which are adjustable on the plate 40 by

means of set screws 47 and 47a in slots 48, 48a, respectively.

The shaft 41 is driven by a pulley 49 and belt 50 from a pulley 51 driven by the drive shaft 33. Accordingly, each of the sections 12 and 13 of belts 14 and 15 will be given a motion in the same longitudinal direction, as shown by the arrows of Figure 1.

The upper plate 40 is adjustable in displacement from base 18 by a pair of standards 52 (one not shown) upstanding from base 18 and a corresponding pair of standards 53 (one not shown) downstanding from plate 40. Each of the standards 52 is fastened to its corresponding standard 53 by a pair of set screws 54, 54a passing through vertical slots in the two standards. By adjusting the spacing of upper roll plate 40 from base 18, by loosening and retightening the set screws the frictional force exerted by sections 12 and 13 upon tape 10 can be brought to any desired value.

As sections 12 and 13 move in the direction shown by the arrows of Figure 1, the frictional engagement of the sections with the portion of the tape which they contact, imparts to that portion, and consequently to the length of the tape following, a constant tangential drive force which urges the tape to motion in the direction of the arrows, and which, when the tape is unrestrained, causes motion of the same. The magnitude of this tangential drive force is held by proper spacing between upper roll plate 40 and base 18 to a value sufficiently moderate so that when the tape 10 is elsewhere firmly grasped, first, the motion of the tape 10 is arrested without any damage resulting to the tape from the moving belts and, second, the belts 14 and 15 are substantially unaffected by the braking action of the stopped tape, continuing, therefore, to move at their usual speed.

The use of the linearly extended sections of 12 and 13 has the advantage that the tape when arrested does not bind to the drive surface, thus unduly amplifying the drive force imparted to the tape.

In order to assure continuous frictional engagement between sections 12 and 13 and tape 10 for the whole area of the sections, a pair of arms 55 (one not shown) hinged on shaft 44 are joined together at their free ends by a pin 56 carrying in freely rotatable relation an idler roll 57. The arms 55 are spring biased by a pair of coil springs 58 (one not shown) so that the idler roll 57 is urged downwardly against belt 15. As a consequence, sections 12, 13 and the portion of tape 10 included therebetween assume a slight downwardly curved shape which increases frictional engagement between the tape and the sections.

Referring now to the means by which magnetic tape 10 may be restrained from motion, spaced away from sections 12, 13 in a direction opposite that of tape motion are a pair of jaws 60, 61 containing another portion of the tape 10. Preferably, jaw 60 is a fixed jaw mounted upon base 18 and having for a jaw face a flat smooth upper surface. The other movable jaw 61 consists of a cross arm 62, a sleeve 63 which is freely pivotable about a transverse pivot pin 64, and a connecting arm 65 which joins cross arm 62 to sleeve 63. The cross arm 62 has a flat lower surface covered with a semi-yieldable material (e.g., rubber) to provide a frictional surface, which is adapted to cooperate with the jaw face of fixed jaw 60 to grasp a portion of the tape between the two jaw faces.

Intermittently, movable jaw 61 is adapted to be separated from fixed jaw 60 by means of the coupling rod 67 which is joined at one end to a median portion of connecting arm 65, and at the other end to the armature of an actuating solenoid 68. When solenoid 68 is energized so that current flows in its coil, the armature of the solenoid is drawn towards the center of the coil, and coupling rod 67 lifts cross arm 62 away from fixed jaw 60 to release the tape 10. Upon deenergization of solenoid 68, under the urging of a pair of springs 69 connected between cross arm 62 and fixed jaw 60, the movable jaw 61 will

be drawn to fixed jaw 60 to grasp the tape 10 between the two jaw faces.

It will be noted that the pivot pin 64, about which movable jaw 61 pivots is spaced away from the tape in a longitudinal direction between the fixed jaw 60 and the fabric belts 14, 15. As a result of the positioning of the pivot pin 64, once jaws 60 and 61 are driven together under the urging of springs 69, the driving force imparted to the tape 10 from sections 12, 13 will draw arm 62 even more tightly down against the fixed jaw 60. Consequently, restraint of the tape upon closure of the jaws is always assured regardless of the amount of driving force imparted to the tape from belts 14, 15 or the strength of springs 69.

In Figure 1 a pair of idler and driver feed rolls 71, 72 and a pair of idler and driver feed rolls 73, 74, respectively advance the tape to form a partial loop 75 and draw the tape away from a partial loop 76. From Figure 1 it is apparent that the loops 75, 76 form temporary tape storage regions which isolate the start-stop motion of the limited extent of tape 10 between the loops from the remainder of the tape, located in part to the left of rolls 71, 72 and in part to the right of rolls 73, 74. It is to be noted that during start-stop motion, the only mass which needs must be accelerated or decelerated by the fabric belt tape drive is the mass of the tape portion lying between the loops, and to a lesser extent the mass of the loop portions of the tape.

Tape 10 carries in longitudinally spaced relation a number of transverse code groups of indicia 80 and a number of indicia 81 marking the position of each code group. The various indicia 80 in each code group are separately scanned by a set of pick-ups 83a-83e (Fig. 2) inclusive mounted upon a pick-up head 84. Similarly the indicia 81 are scanned by a pick-up 85 on the head 84. In order to maintain proper contact between the tape and the pick-up, tape 10 is fed past a fixed guide bar 86 preceding the head 84 and past another fixed guide bar 88 following head 84.

Referring now to Figure 2, the block designated 100 represents an electronic photocomposer as disclosed in the application of Battle Klyce and F. Kimball Loomis, Serial No. 343,116, filed March 18, 1953, for "Photocomposing Mechanism." The photocomposer 100 is adapted, responsive to different code groups of indicia 80, to automatically perform operations associated with a printing apparatus, as, for example, the printing of characters on a carrier medium, the spacing of these characters as printed, the creation of word spaces, and the shifting of the material being printed to a new line or column.

Assume now that one of these mentioned operations has just been performed by the photocomposer 100. In such case the tape 10 will be in a state of high speed motion, in a direction coming out of the surface of the figure as shown in Figure 2. This motion continues until a new code group, signified by a given row of indicia 80 in the tape 10, is swept past the pick-up head 84. At such time the information carried by the various indicia 80 is converted into a corresponding group of electric signals by the change in magnetic flux experienced by the pick-ups 83a-83e inclusive as the indicia 80 move past them. Simultaneously, the indicium 81 is swept past the pick-up 85 to produce another electric signal, which, after a short delay by passage through a delay circuit 101, is applied to a multivibrator 102. The multivibrator 102, which is of a conventional bistable type, is normally conditioned to supply a positive signal to the grid 103 of a triode 104. Upon receiving the signal from delay circuit 101, the multivibrator 102 reverses its conductivity states to drive grid 103 negative with the result that tube 104 is cut off.

The plate cathode path of tube 104 is connected in a loop circuit with the coil 106 of solenoid 68 and a source of operating voltage and current (not shown). Normally current flows through coil 106 to maintain the armature 107 of the solenoid 68 in the center of the coil, solenoid

68 when thus energized maintaining, through coupling rod 67, the jaws 60 and 61 in a mutually separated position. When tube 104 is cut off, however, solenoid 68 is deenergized, jaws 60 and 61 fly together under the action of springs 69, the motion of the tape is arrested and, as previously stated, the jaws 60 and 61 become self-holding in their closed position. Thus immediately after an indicium 81 sweeps past pick-up 85, the tape 10 is caused to assume a state of dwell.

Upon completion of one of its mentioned operations, the photocomposer 100 produces a second signal which also is applied to the multivibrator 102 to again reverse the state of the same. Multivibrator 102, thereupon, again applies a positive signal to the grid 103 of the tube 104, and solenoid 68 is reenergized to cause a corresponding release of tape 10 by jaws 60 and 61. Upon being released tape 10 rapidly accelerates to a state of high speed motion, in which state it continues until another code group of indicia 80 and an indicium 81 sweeps past the pick-ups, at which time the cycle just described repeats itself.

The tape driving mechanism described may also be employed where (as shown in Fig. 3) separate code groups of indicia 80a of either positive or negative polarity are disposed along the length of a narrow magnetic tape 10a. In such case only a single pick-up 85a need be utilized, the pick-up 85a generating a sequence of signals as the various indicia 80 in a code group sweep past the same. Upon the scan of a full code group by the single pick-up, an electric signal is supplied from, for example, indicia counting means (not shown) to the multivibrator 102 to cause arrest of the tape motion as described.

Figure 4 shows a form of tape driving mechanism advantageous in that only the indicia-free (upper) side of the magnetic tape is frictionally contacted, thus eliminating wear on the magnetic signal sensitive coating. The illustration of Figure 4 represents a sectional view taken through the axis of a roll 39b (identifiable with roll 39 of Fig. 1) and looking in the direction of tape motion.

Roll 39b, which is supported by a shaft 44b carries (in conjunction with another roll, not shown), a fabric belt 15b in a manner similar to that shown for fabric belt 15 (Fig. 1). The belt 15b has a lower straightaway section extending rearwards of the drawing plane in Figure 4, this section being adapted by frictional engagement to impart a continuous driving force to a narrow tape 10b of the type shown in Figure 3, tape 10b being adapted to carry indicia on the lower side thereof.

For maintenance of continued frictional contact between belt 15b and tape 10b, a blower box 110 is disposed below the tape 10b. The blower box 110 has formed in the interior thereof an air chamber 111 and on the upper surface thereof a hemi-cylindrical groove 112 aligned and coextensive with the straightaway section of belt 15b. Air chamber 111 communicates with groove 112 by means of a narrow slot 113 running (rearward from the drawing plane in Fig. 4) the full length of the groove.

In operation air chamber 111 by means of a port 114 receives compressed air from an air supply (not shown). The air so received is forced from chamber 111 through slot 113 to raise the air pressure in the space included within groove 112. The increased air pressure in this space acts to blow tape 10b with constant force against the straightaway section of belt 15b. A small clearance between the upper surface of blower box 110 and tape 10b (when in contact with belt 15b) permits air leakage to assure a constant air flow through the blower box.

Figure 5 shows in sectional view a mechanism involving no frictional force, for imparting a continuous driving force to a magnetic tape. In the figure, a narrow tape 10c of the type shown in Figure 3 is fed past a fixed guide bar 88c (identifiable with bar 88 of Fig. 1) to a vacuum box 120 having an interior chamber 121 of only slightly greater width (taken rearward of the drawing plane) than

the tape width. Tape 10c is led into and out of the vacuum box through slits 122 and 123 permitting only slight tape clearance. Both slits 121 and 122 have faired approaches for either direction of approach to the slits.

Between slits 122 and 123 the tape 10c forms a partial loop 76c (identifiable with loop 76 in Fig. 1). Since chamber 122 and tape 10c are of approximately the same width, the space located exterior of loop 76c but interior to the walls of chamber 122 is sufficiently air tight to support a vacuum created in the space by a vacuum source (not shown) communicating with the space through a port 124.

The vacuum so created tends to pull tape 10c from the left to form a continuously larger loop 76c. Loop 76c, however, is monitored for size by a photosensitive device 125 (identifiable with device 77' of Fig. 1) so that when the bottom of loop 76c drops below the level of device 125, tape 10c is drawn to the right and out of the vacuum box 120 by cooperating idler and driver rolls 73a and 74a (identifiable with rolls 73 and 74 of Fig. 1), driver roll 74a being limited by conventional means (not shown) to rotate only in its appropriate feed direction. The movement of roll 74a is controlled by device 125 in the mode previously described with respect to photo-sensitive device 77' and roll 74 (Fig. 1).

It is apparent, therefore, that a continuous force urging tape 10c rightwards is exerted by the vacuum in vacuum box 120. At the same time, whenever loop 76c in the vacuum box becomes too large the tape 10c is advanced out of the vacuum box to re-establish the proper size for the loop.

It will be noted that the tape driving mechanisms of Figures 1, 4 and 5 are commonly related in that each distributes the driving force imparted to the tape over the area of an extended portion of the tape. Such force distribution is advantageous in that it permits impartment of an effective driving force to the tape while at the same time causing distribution over the mentioned area of the stress set up in the tape upon being arrested from motion.

The invention thus provides a novel and highly effective motion control mechanism for producing alternating states of motion and dwell in a strip of elongated material, as, for example, a magnetic tape. By imparting a continuous drive force to the strip and by intermittently arresting the motion of the tape by grasping another portion thereof with a pair of jaws, the time lag required for travel between a state of dwell and a state of high speed motion, or the reverse, can be minimized. Moreover, as a result of the particular jaw structure employed, the jaws when once closed become self-holding, thus rendering the mechanism independent of variations in the drive force imparted to the tape or the force which initially draws the jaws together. Moreover, the motion control mechanism may be gainfully employed with a record controlled utilization device in which the tape is advanced after completion of each operation by the device and is stopped each time the device picks up a signal corresponding to a new group of indicia.

The embodiments shown in the drawings and described herein are obviously susceptible to considerable modification in form and detail within the spirit of the invention. The embodiments, therefore, are to be regarded as illustrative only and not as limiting the scope of the following claims.

I claim:

1. In a utilization device adapted to perform a set of operations separately initiated by the scanning of corresponding separate indicia spaced along an elongated magnetic tape, said device producing first and second signals respectively upon completion of each operation and upon scanning of a particularly characterized indicium, in combination with said device, distributed force drive means adapted to impart over the area of a lengthwise extending unwrapped portion of said tape a continuous pulling

force urging motion thereof, a pair of jaws adapted for selectively freeing and restraining another pulled portion of said tape to correspondingly permit and arrest said motion, and means responsive to said first and second signals, respectively, for rendering said pair of jaws selectively operative to free and to restrain said other portion.

2. In a utilization device adapted to perform a set of operations separately initiated by the scanning of corresponding separate indicia spaced along an elongated magnetic tape, said device producing first and second signals respectively upon completion of each operation and upon scanning of a particularly characterized indicium, in combination with said device, distributed force drive means adapted to impart over the area of a lengthwise extending unwrapped portion of said tape a continuous pulling force urging motion thereof, a pair of jaws adapted for selectively freeing and restraining another pulled portion of said tape by mutual separation and closure of said jaws, respectively, to correspondingly permit and arrest said motion, means responsive to said first and second signals, respectively, for separating and closing said jaws, and means responsive to said force as exerted by said tape upon said jaws when in closed position for holding said jaws in closed position.

3. In a utilization device adapted to perform a set of operations separately initiated by the scanning of corresponding separate indicia spaced along an elongated magnetic tape, said device producing first and second signals respectively upon completion of each operation and upon scanning of a particularly characterized indicium, in combination with said device, distributed force drive means adapted to impart over the area of a lengthwise extending unwrapped portion of said tape a continuous force urging motion thereof, a fixed jaw and a pivoted jaw mutually adapted to selectively free and restrain another portion of said tape respectively upon movement of said pivoted jaw to open and closed positions respectively with reference to said fixed jaw, said jaws by freeing and restraining said other portion correspondingly permitting and arresting said motion, a pivot for rendering said pivoted jaw movable to said open and closed positions, said pivot being disposed at a location fixedly spaced normal to said tape and longitudinally between said fixed jaw and said means on the same side of said tape as said pivoted jaw, said pivot location and said force on said tape conjointly rendering said pivoted jaw self-holding in said closed position, and means responsive to said first and second signals for correspondingly moving said pivoted jaw to said open and closed positions.

4. Apparatus in which a magnetic tape is adapted for signal transfer purposes to be intermittently moved in a predetermined direction in a predetermined path, said apparatus comprising, tape guide means establishing a configuration for said path in which a length thereof is disposed between first and second parts of said path in which said tape is adapted to form respective first and second slack loops, said first path part, path length and second path part being disposed in the order named in said direction, a magnetic signal transfer head disposed along the extent of said path at a mediate position in said path length to provide for signal transfer between said head and said tape when said tape moves past said head, tape drive means disposed at a position along the extent of said path between said head and the far end of said second slack loop, said drive means being adapted by a yieldable cooperation with an unwrapped portion of said tape at said last named position to impart to said unwrapped portion a continuous drive force exerted in said direction and transmitted from said unwrapped portion through said tape in said length of path to continuously urge motion of said tape out of said first slack loop, past said head, and into said second slack loop, and a pair of jaws having cooperating faces and disposed along the extent of said path on opposite sides of said tape at a position between said head and said first slack loop, said jaws being adapted by alter-

nately opening from each other and closing towards each other to alternately release said tape and to grasp said tape by said faces with a restraining force exceeding said drive force, said jaws being thereby adapted to impart a start-stop motion to a portion of said tape extending out of said first slack loop through said path length and into said second slack loop.

5. Apparatus as in claim 4 in which at least one of said jaws is adapted to relatively open and close with the other jaw by movement of said one jaw about a pivot, and in which said pivot is at a location which is spaced normally of said tape on the same side of said tape as said one jaw, and which is offset in said direction from the place where said jaw faces are adapted to grasp said tape, said one jaw thereby being adapted to be held in closed position by the drive force transmitted through said tape when said jaw faces are closed thereon.

6. Apparatus in which a magnetic tape is adapted for signal transfer purposes to be intermittently moved in a predetermined direction in a predetermined path, said apparatus comprising, tape guide means establishing a configuration for said path in which a length thereof is disposed between first and second parts of said path in which said tape is adapted to form respective first and second slack loops, said first path part, path length and second path part being disposed in the order named in said direction, a magnetic signal transfer head disposed along the extent of said path at a mediate position in said path length to provide for signal transfer between said head and said tape when said tape moves past said head, at least one continuous belt having a linearly-extended tape-driving surface tangential to said path at a position between said head and said second slack loop, said driving surface being adapted to be continuously urged to movement in said direction along said path, means to maintain an unwrapped portion of said tape at said last named position in yieldable frictional cooperation with said drive surface, whereby said drive surface is adapted to impart to said unwrapped portion a continuous drive force exerted in said direction and transmitted from said unwrapped portion through said tape in said length of path to continuously urge said motion of said tape out of said first slack loop, past said head, and into said second slack loop, a pair of jaws having cooperating faces and disposed along the extent of said path on opposite sides of said tape at a position between said head and said first slack loop, said jaws being adapted by alternately opening from each other and closing towards each other to alternately release said tape and to grasp said tape by said faces with a restraining force exceeding said drive force, said jaws being thereby adapted to impart a start-stop motion to a portion of said tape extending out of said first slack loop through said path length and into said second slack loop, and belt drive means to continuously urge said belt drive surface to said movement thereof by a force exceeding said drive force, whereby said surface continuously moves but is adapted to slip relative to said tape when said tape is grasped by said jaws.

7. Apparatus in which a magnetic tape is adapted for signal transfer purposes to be intermittently moved in a predetermined direction in a predetermined path, said apparatus comprising, tape guide means establishing a configuration for said path in which a length thereof is disposed between first and second parts of said path in which said tape is adapted to form respective first and second slack loops, said first path part, path length and second path part being disposed in the order named in said direction, a magnetic signal transfer head disposed along the extent of said path at a mediate position in said path length to provide for signal transfer between said head and said tape when said tape moves past said head, a pair of continuous belts having respective linearly-extended tape-driving surfaces opposite each other and on opposite sides of said tape at a position along the extent of said length of path between said head and

said second slack loop, each of said surfaces being adapted to be continuously urged to movement in said direction along said path, and said surfaces being adapted to be in yieldable frictional cooperation with opposite sides of an unwrapped portion of said tape at said last named position to impart to said unwrapped portion a continuous drive force exerted in said direction and transmitted from said unwrapped portion through said tape in said length of path to continuously urge said motion of said tape out of said first slack loop, past said head, and into said second slack loop, a pair of jaws having cooperating faces and disposed along the extent of said path on opposite sides of said tape at a position between said head and said first slack loop, said jaws being adapted by alternately opening from each other and closing towards each other to alternately release said tape and to grasp said tape by said faces with a restraining force exceeding said drive force, said jaws being thereby adapted to impart a start-stop motion to a portion of said tape extending out of said first slack loop through said path length and into second slack loop, and belt drive means to urge each of said belt surfaces to said movements thereof by a force exceeding said drive force, whereby said surfaces move but are adapted to slip relative to said tape when said tape is grasped by said jaws.

8. Apparatus in which a magnetic tape is adapted for signal transfer purposes to be intermittently moved in a predetermined direction in a predetermined path, said apparatus comprising, tape guide means establishing a configuration for said path in which a length thereof is disposed between first and second parts of said path in which said tape is adapted to form respective first and second slack loops, said first path part, path length and second path part being disposed in the order named in said direction, a magnetic signal transfer head disposed along the extent of said path at a mediate position in said path length to provide for signal transfer between said head and said tape when said tape moves past said head, at least one continuous belt having a linearly-extended tape driving surface tangential to said path at a position between said head and said second slack loop, said driving surface being adapted to be continuously urged to movement in said direction along said path, pneumatic means adapted by generating a flow of air to produce on an unwrapped portion of said tape at said last named position an air pressure which is greater on the side of said portion away from said surface than on the side of said portion towards said surface to thereby maintain said unwrapped portion in yieldable frictional cooperation with said drive surface, whereby said drive surface is adapted to impart to said unwrapped portion a continuous drive force exerted in said direction and transmitted from said unwrapped portion through said tape in said length of path to continuously urge said motion of said tape out of said first slack loop, past said head, and into said second slack loop, a pair of jaws having cooperating faces and disposed along the extent of said path on opposite sides of said tape at a position between said head and said first slack loop, said jaws being adapted by alternately opening from each other and closing towards each other to alternately release said tape and to grasp said tape by said faces with a restraining force exceeding said drive force, said jaws being thereby adapted to impart a start-stop motion to a portion of said tape extending out of said first slack loop through said path length and into said second slack loop, and belt drive means to continuously urge said belt drive surface to said movement thereof by a force exceeding said drive force, whereby said surface continuously moves but is adapted to slip relative to said tape when said tape is grasped by said jaws.

9. Apparatus in which a magnetic tape is adapted for signal transfer purposes to be intermittently moved in a predetermined direction in a predetermined path, said apparatus comprising, tape guide means establishing a configuration for said path in which a length thereof is disposed between first and second parts of said path in which said tape is adapted to form respective first and second slack loops, said first path part, path length and second path part being disposed in the order named in said direction, a magnetic signal transfer head disposed along the extent of said path at a mediate position in said path length to provide for signal transfer between said head and said tape when said tape moves past said head, means to restrain said tape from being drawn into said second slack loop from the side thereof away from said path length, pneumatic means to produce on the inner side of said second slack loop a cushion of air at a pressure which is continuously greater than that of the air in the region on the outer side of said last named loop to thereby tend to continuously enlarge said second slack loop, said air cushion being adapted to yieldably cooperate with an unwrapped portion of said tape in said second slack loop to impart to said unwrapped portion a continuous drive force exerted in said direction and transmitted from said unwrapped portion through said tape in said length of path to continuously urge said motion of said tape out of said first slack loop, past said head, and into said second slack loop, a pair of jaws having cooperating faces and disposed along the extent of said path on opposite sides of said tape at a position between said head and said first slack loop, said jaws being adapted by alternately opening from each other and closing towards each other to alternately release said tape and to grasp said tape by said faces with a restraining force exceeding said drive force, said jaws being thereby adapted to impart a start-stop motion to a portion of said tape extending out of said first slack loop through said path length and into said second slack loop, and means responsive to enlargement of said second slack loop to produce movement of said tape in said direction out of said second slack loop.
